UNITED STATES PATENT OFFICE.

JOHN EASTER MINTER, OF MACON, GEORGIA.

APPARATUS FOR SETTING UNBURNED WARE IN KILNS FOR BURNING.

SPECIFICATION forming part of Letters Patent No. 726,822, dated April 28, 1903.

Application filed October 23, 1902. Serial No. 128,429. (No model.)

To all whom it may concern:

Be it known that I, JOHN EASTER MINTER, of Macon, in the county of Bibb and State of Georgia, have invented certain new and useful Improvements in Apparatus for Setting Unburned Ware in Kilns for Burning, of which the following is a specification.

The object of my invention is to provide an apparatus for rapidly setting heavy molded articles in a kiln without liability of breaking, chipping, or otherwise disfiguring the ware handled.

The invention is particularly designed to be associated with round downdraft sewer-pipe kilns, and is primarily designed for handling unburned sewer-pipes; but the invention is adapted for other uses, as will suggest themselves when the same is better understood.

20 The invention includes the parts, combination of parts, and details of construction, as will be hereinafter described, and fully pointed out in the claims.

25 While the invention is susceptible of various modifications, I have illustrated in the accompanying drawings what I now conceive to be the preferred embodiment thereof.

As illustrated in said drawings, Figure 1 shows the invention in side elevation associated with a round downdraft sewer-kiln, which in said figure is shown in vertical sectional elevation. Fig. 2 is a detail plan view of the carrying-arm. Fig. 3 is a detail longitudinal sectional view of the shaft carrying 35 said arm and the journal-bearing provided for said shaft, and Fig. 4 is a detail view of the connection between one of the frame-pieces of the external swinging frame and the supporting-mast for said frame. Fig. 5 is a detail view of a modification. Fig. 6 is a detail view of the lifting-crab.

As before premised, the invention is primarily intended to be employed in connection with a round downdraft sewer-kiln, and 45 in the accompanying drawings the apparatus is illustrated in this association. The kiln, as shown in section in Fig. 1, includes a main or outer wall *a*, an inner flash or fire wall *b*, and a crown *c*, in which an opening *c'* is axially arranged. Secured outside and in juxtaposition to the outer wall *a* of the kiln in a suitable base or foundation is a vertical mast

d, upon the upper portion of which a swinging frame *e* is mounted. This frame preferably comprises three horizontal frame members (designated *e'*, *e''*, and *e'''* in the accompanying drawings) and an obliquely-extending brace member *e'*, bolted at its upper and lower ends to the members *e'*, *e''*, respectively, and intermediately of its length to the central portion of the member *e''*. The mast is preferably turned down or reduced at the point of attachment of the horizontal members *e'*, *e''*, and *e'''* to provide cylindrical bearing portions therefor, upon each side of which shoulders 65 are arranged which center said horizontal members, said shoulders being formed by turning down the mast, as described. The horizontal members are each formed of two parallel strips which embrace at one of their 70 ends opposite sides of the reduced portions of the masts, and blocks *k* are inserted between said strips adjacent to the mast to complete the bearing-boxes which receive the reduced portions of the latter. The particular construction of the swinging frame and the manner of mounting the same upon the mast constitute but a subordinate feature of the invention, and the same may be varied or changed within a wide range without departing from the spirit of my invention. The swinging frame constitutes what is termed an "exterior support," because it is exterior to the interior of the kiln and supports a second supporting part located within 85 the kiln. The particular manner of mounting the swinging frame or exterior support, as before premised, is not of primary importance, and various means or constructions, such as will readily suggest themselves, may 90 be employed for the purpose.

Mounted rigidly in the free end of the frame *e* is a vertically-arranged sleeve *f*, which is located such a distance from the mast *d* relative to the diameter of the kiln 95 with which the apparatus is associated that said sleeve will register with the crown-opening *c'* when the frame *e* is swung to bring the free end thereof over the center of said kiln.

Removably mounted in the sleeve *f* is a hollow shaft *g*, which depends through the lower end of the same, passes through said opening *c'* into the interior of the kiln, and carries at its lower end a laterally-extending

arm *h* of any desired length. The shaft *g* is removably journaled in the sleeve *f*, and the arm *h* is removably mounted upon the end thereof for a purpose to be described herein-
5 after. The shaft *g* is detachably supported in the sleeve *f* by means of a collar *g'*, which is removably secured to the upper end of the shaft *g*, which projects above the upper end of said sleeve, the lower edge of the collar
10 thus finding a bearing upon the upper edge of the sleeve. The arm *h* is detachably fitted to the lower end of the shaft *g*, and from the free end thereof a brace-rod *h'* extends obliquely to a bracket *m*, bolted upon the shaft
15 *g* between the lower end of the latter and the lower end of the sleeve *f*. This bracket *m* is provided with an opening *m'*, with which the hook *n* on the brace-rod *h'* detachably engages, said rod being provided with a turn-
20 buckle in the length thereof to regulate the tension of the same.

Associated with the arm *h* is a guide pulley or roller *s*, which is adapted to be shifted longitudinally of the former. A second pulley is
25 journaled at a point adjacent to the lower end of the shaft *g*, another pulley is journaled to the lower end of the brace-bar *e* above the upper end of said shaft *g*, and a fourth pulley is journaled to the upper end of the mast
30 *d*. Over said pulleys and through the bore of the shaft *g* a rope or cable is guided, which is secured at one end to a suitable hoist, as a winding-drum, winch, or the like, and at its other end to a clamping member, which is
35 adapted to engage the pipes or other articles to be set within the kiln. This clamping member is preferably formed by a crab *r*, designed to engage with the collars of the pipes. The pulley or roller *s* may be adjustably con-
40 nected to and supported from the arm *h* in any desired manner, and in the accompanying drawings two convenient constructions for this purpose are illustrated. In Fig. 1 the arm *h* is comprised of two parallel strips
45 spaced a distance apart, provided with a plurality of equidistant-spaced alining openings which are designed to receive the ends of the journal of the roller or pulley *s*. In Fig. 5 the arm *h* is shown as constructed of an
50 I-beam, upon the flanges of which a carriage *s'*, in which the pulley *s* is journaled, is supported, said carriage being adjustable longitudinally thereof.

The amount of free space in the crown of a
55 kiln of ordinary construction above the upper tier of stacked pipes is quite limited, the arm *h* just clearing the upper ends of said pipes when turned about its axis. It is important, therefore, that the crab *r* be of such
60 construction that it will hold the upper end of the pipe which is being set in close juxtaposition to the arm, so that the lower end of said pipe will clear the upper end of the pipes forming the second tier of the stack upon
65 which the third tier is being placed. The crab (illustrated in Fig. 5) has been found to meet the requirements in a satisfactory man-

ner. This device, as shown, comprises gripping ends *1*, designed to engage beneath the edge of the collars of the pipes, a depressed connecting portion *2*, which depends into the interior of the pipe when the crab is in place thereupon, and a central offset loop *3*, with which a knot in the end of the lifting cable or rope engages.
75

In the operation of the apparatus the outer row or stack of pipes is first set in the kiln, the pipes being conveyed within the kiln through the door in the side thereof upon a suitable car or truck. To lift the pipes from the car or truck, the cable or rope is slackened off, the crab *r* engaged with the collar on the pipe to be set, and the hoist operated, which will wind up the cable and lift the pipe to the desired elevation. After the outer row
80 is completely stacked, the pulley or roller *s* is shifted along the arm *h* toward the axis of the latter to bring the pulley the same radial distance from said axis as the center of the second circumferential row to be set. The procedure described in connection with the setting of the outer row is then followed until the second row is completely stacked, when the pulley or roller is again shifted along the arm *h* to bring the same in position
85 to set the succeeding row within the kiln. As will be appreciated, the articles to be set after they are raised to the desired elevation can be carried completely around the kiln and let down in any desired radial position
90 to set the succeeding row within the kiln. As will be appreciated, the articles to be set after they are raised to the desired elevation can be carried completely around the kiln and let down in any desired radial position
95 to set the succeeding row within the kiln. As will be appreciated, the articles to be set after they are raised to the desired elevation can be carried completely around the kiln and let down in any desired radial position
100 to set the succeeding row within the kiln. As will be appreciated, the articles to be set after they are raised to the desired elevation can be carried completely around the kiln and let down in any desired radial position
105 to set the succeeding row within the kiln. As will be appreciated, the articles to be set after they are raised to the desired elevation can be carried completely around the kiln and let down in any desired radial position
110 to set the succeeding row within the kiln. As will be appreciated, the articles to be set after they are raised to the desired elevation can be carried completely around the kiln and let down in any desired radial position
115 to set the succeeding row within the kiln. As will be appreciated, the articles to be set after they are raised to the desired elevation can be carried completely around the kiln and let down in any desired radial position
120 to set the succeeding row within the kiln. The apparatus may be as quickly reassembled to again set the kiln by a reverse procedure.
125

The construction and operation of my invention will be readily understood upon reference to the foregoing description and accompanying drawings, and it will be appreciated that the parts and combinations may be varied within a wide range without departing from the spirit of the same.

What I claim as my invention, and desire to secure by Letters Patent, is—

1. The combination with a kiln having an opening through the crown thereof arranged substantially axially of the same, of a sup-

- port located without the interior of the kiln mounted to have one of its ends brought into and carried out of register with said opening, an interior support, means depending from 5 the free end of the first-named support projecting through the crown-opening and engaging said interior support to carry the latter, and means coacting with said interior support for engaging the ware to be set, substantially as described.
2. The combination with a kiln having an opening through the crown thereof arranged substantially axially of the same, of a support located without the interior of the kiln 15 mounted to have one of its ends brought into and carried out of register with said opening, an interior support, means journaled in said end of the exterior support depending therefrom through the crown-opening engaging 20 the interior support to carry the same, and means associated with said interior support for engaging the ware to be set, substantially as described.
3. The combination with a kiln having an opening through the crown thereof, an exterior movable support, a shaft journaled in 25 said support depending through said crown-opening and of such relative size that it may be removed therethrough, an interior support carried by said shaft of such size that it may 30 be removed through said opening, and means for adjusting the ware to be set associated with the interior support, substantially as described.
4. The combination with a kiln having an opening through the crown thereof, of a movable support mounted to be carried into and moved out of register with said opening, means depending from said support extending 35 through the crown-opening, an interior support carried by said means, and means associated with the interior support for engaging the ware to be set, substantially as described.
5. The combination with a kiln having an axial opening in the crown thereof, of a setting apparatus comprising an exterior support, an interior support, means carried by 45 said exterior support depending through said crown-opening and carrying the interior support, and a lifting and supporting cable, substantially as described.
6. The combination with a kiln having an opening in the wall thereof, of an apparatus 55 for setting unburned ware therein comprising a support arranged without the kiln, a support arranged within the latter, a shaft carrying the second support, said shaft passing through the kiln-opening and being rev- 60 olubly mounted in the first support, and a lifting and supporting cable, substantially as described.
7. The combination with a kiln having an opening in the crown thereof, of a setting apparatus comprising a mast located without 65 said kiln and in close proximity thereto, a support revolvably mounted thereupon, a sleeve secured in the free end of said support designed to be registered with said opening, a shaft journaled in said sleeve and depending 70 therefrom through said opening, a laterally-extending arm secured to the end of said shaft, and a rope or cable, substantially as described.
8. The combination with a kiln having an opening in the crown thereof, of a setting apparatus comprising a vertical mast, a swinging frame mounted thereupon, a sleeve journaled in the free end of said frame, a hollow shaft journaled in said sleeve and depending 75 therefrom through said opening in the kiln, an arm secured to the end of said shaft and extending laterally therefrom, guide pulleys or rollers, a cable guided over said pulleys and through said hollow shaft, and an engaging 80 member carried by said cable, substantially as described.
9. The combination with a kiln having an opening in the crown thereof, of a setting apparatus comprising a vertical mast, a swinging frame mounted thereupon, a sleeve fixed 85 in the free end of said frame, a shaft journaled in said sleeve and removable therefrom, an arm detachably secured to the lower end of said shaft and extending laterally from the 90 same, a cable and an engaging member carried thereby, substantially as described.
10. The combination with a kiln having an opening in the crown thereof, of a setting apparatus comprising a mast, a swinging frame, 95 a sleeve secured in the free end thereof, a hollow shaft journaled therein and depending through the opening in said kiln, an arm secured to the lower end of said shaft and extending laterally therefrom, guide pulleys or 100 rollers mounted adjacent to the upper and lower ends of said shaft, a guide-pulley mounted in said arm to move longitudinally of the same, a cable guided over said pulleys and through said hollow shaft, and an engaging 105 member secured to the end of said cable, substantially as described.
11. The combination with a kiln having an opening in the crown thereof, of a setting apparatus comprising an external swinging frame, a revolvably-mounted shaft depending 115 therefrom through the opening in the crown of said kiln, an arm detachably secured to the lower end of said shaft and extending laterally from the same, a brace-rod secured at 120 one end to the free end of said arm and detachably secured at its other end to said shaft, a cable and an engaging member secured to one end thereof, substantially as described.
12. The combination with a kiln having an axial opening in the crown thereof, of a setting apparatus comprising a mast, a swinging frame mounted thereupon, a sleeve designed 125 to be registered with said opening secured in the free end of said frame, a hollow shaft removably journaled in said sleeve depending

from the lower end thereof through said axial opening in the kiln, a bracket secured to said shaft, an arm detachably secured to the lower end of the shaft and extending laterally from the same, a brace-rod secured at one end to said arm and at the other end to said bracket, pulleys or rollers mounted adjacent to the upper and lower ends of said shaft, a pulley mounted in said arm to move longitudinally of the same, a cable guided over said pulleys and through said shaft, and an engaging

member secured to one end of said cable, substantially as described.

In testimony whereof I have hereunto signed my name, in the presence of two attesting witnesses, at Macon, in the county of Bibb and State of Georgia, this 9th day of October, 1902.

JOHN EASTER MINTER.
